UNITED STATES PATENT OFFICE

2,461,398

PORTABLE DOOR FASTENER

Henry F. Sands, Cranston, R. I.

Application May 12, 1947, Serial No. 747,455

6 Claims. (Cl. 292—297)

1

This invention relates to a portable door fastener.

It is desirable in many instances to provide a door fastener which will serve to prevent the opening of a door either by serving as a primary lock or by being supplemental to a lock already existing on the door. Devices of this general character are usually complicated or do not exert a pressure upon the door at all times so that rattling of the device is avoided. Many of these devices are not susceptible to use on doors of different thicknesses.

One of the objects of this invention is to provide a door fastener which will be readily portable and which may be carried about with the person from place to place as he is traveling.

Another object of this invention is to provide a door fastener which is so arranged that it will fit upon doors of varying thicknesses and thus be adapted for use in a wide variety of locations.

Another object of this invention is to provide a door fastener which is extremely simple in construction and one which may be made with a minimum number of parts and a minimum of assembly operations.

Another object of this invention is to provide a device which may be formed by stampings and assembly operations.

Another object of this invention is to provide a device the adjustment of which and the locking of which all occur in the same motion of a single part.

With these and other objects in view, the invention consists of certain novel features of construction as will be more fully described and particularly pointed out in the appended claims.

In the accompanying drawings:

Fig. 1 is a perspective view of the fastener complete;

Fig. 2 is a top plan view with the locking member swung to a detached position;

Fig. 3 is a sectional view illustrating the device in locking position and in its assembled relation to a door and door jamb.

In proceeding with this invention, I provide a plate with one end offset or flanged so as to enable it to be inserted into an opening provided for a door latch, or it may be inserted directly into the door jamb in some cases. This plate is provided with a plurality of openings forming abutments at varying spaced distances for the accommodation of doors of varying thicknesses. A carriage is provided which will slide on this plate and which will carry a member pivoted thereon for engagement with any one of the

2

selected openings to provide an abutment surface, while this member has a cam surface for engaging the door, with the arrangement such that when the member is swung about its pivot, one part of it serves to engage and slide along an abutting surface, while the other part engages the door and forces it toward closed position. Thus, the member is such as to take up any differences in dimension between varying abutting surfaces and hold the door firmly in position when moved to locked location.

With reference to the drawings, more particularly 10 designates a plate which is formed of a strip of sheet stock which is flanged at one end 15 as at 11 which flange may be provided with a plurality of teeth 12 to enter the door jamb, or the flange, as a whole, may enter a recess in the door jamb which is designed for the reception of a latch or lock. The plate will be of such a thickness as to extend between the edge of the door and the door jamb and outwardly from between these two parts. A series of holes 13 are provided in the plate which form abutting surfaces 14 at varying distances from the door and from the flange 11.

A slide or carriage 15 has a plate 16 with sides 17 folded therefrom and turned inwardly as at 18 to be parallel to the plate 16 and are then turned outwardly to provide flanges 19 in a spaced relation. This slide 15 thus embraces the plate 10 and may be moved longitudinally along the plate over the openings 13 which are provided therein. A locking member designated generally 20 is pivoted by a pin 21 between the out-turned flanges 19 of the slide and is of a thickness to enter between the out-turned flanges 19. This member 20 comprises a body 22 from which there extends an arm 23 which is provided with a plurality of holes 24. The arm is of an arcuate shape with its center at the axis of the pivot pin 21, and this arm is of a dimension to pass through any selected opening 13 in the plate so that its concave edge 25 will engage the abutment surface 14 of the plate which is formed by the hole 13. The outer end, or the end distant from the pivot of this member, designated 26 is of a generally cam shape and is of a shape other than a true arc from the pivot and serves to engage the door, the arrangement being such that as the member 20 swings about its pivot 21, the surface 26 will force the door farther away from the pivot. Holes or openings 27 are provided in the out-turned flanges 19; and, as any of the holes 24 in the arm register with these holes 27, the arm may be locked in position by a pin 28 which

is passed through the registering openings or the pin may pass through one of the openings 24 in the arm as the arm extends through the slide and would be prevented from being withdrawn through the slide by reason of such location of the pin. In order to maintain the pin 28 assembled with the device, a flexible thong or chain 30 is attached to the pin 28 and also attached by means of the link 31 to the hole 32 in the end of the plate. When not in use, the pin 28 may be lodged through the opening 34 in the projection 35 which is mounted on the slide.

A flange 33 may be secured to the side of the slide nearest the door to engage the door jamb in some cases where desired.

In order to illustrate the use of this device, I have shown in section a door 36 and a door jamb 37 in which there is a recess 38 for a latch or the like. When the door is open, the plate is positioned along the surface of the door jamb at 39 with its flange 11 located in the recess 38. The door is then closed and the slide moved toward the door until the flange 33 engages the door jamb. The locking member 28 will be retracted or in substantially the position shown in Fig. 2 during the time that the slide is moved to position shown in Fig. 3. The locking member is then swung about its pivot, from the position shown in Fig. 2, so that the arm 23 will pass through one of the openings 13 and engage an abutment surface 14. Surfaces 26, during this movement, will engage the outer surface 40 of the door and force it toward the surfaces 41 of the door jamb which it engages. The more the pressure is placed upon the member 28, the tighter the door will be forced against the surface 41. When the member is substantially in the position shown in Fig. 3, it may be locked in this position by passing the pin 28 through the openings 27 and 24 to prevent retraction of the locking member. If, however, it is desired that the member be locked without the use of the opening 27, or if the opening 27 does not come into registry, the pin 28 may be passed through one of the openings 24 as shown in Fig. 1.

I claim:

1. A portable door fastener comprising a plate engageable between the door and door jamb, means on the plate to lock the plate against removal from such position when the door is closed, said plate being provided with a plurality of abutment surfaces at spaced intervals, a slide movable along said plate, and a locking member pivoted on said slide and having an arm to engage and slide along a selected one of the abutment surfaces to hold the slide in adjusted position and a cam surface on the member to engage a door to force the door away from said abutment surface as the locking member is swung on its pivot.

15 2. A portable door fastener as in claim 1 wherein in additional means lock the member in one relative position of swinging about its pivot.

3. A portable door fastener as in claim 1 wherein a plurality of holes are provided in said arm to receive a removable pin.

20 4. A portable door fastener as in claim 1 wherein a plurality of holes are provided in said arm and a hole is provided in said slide to register with one of said holes and a pin extends through the registered holes to lock the member in position.

25 5. A portable door fastener as in claim 1 wherein in said means is a flange adapted to enter a recess in the door jamb and is formed from the same material as said plate.

30 6. A portable door fastener as in claim 1 wherein in said abutment surfaces are provided by holes in said plate.
